CLAIM

The ornamental design for display screen or portion thereof with animated graphical user interface for an equipment management system, as shown and described.

DESCRIPTION

The patent or application file contains at least one drawing executed in color. Copies of this patent or patent application publication with color drawing(s) will be provided by the Office upon request and payment of the necessary.

FIG. 1 is a front view of a display screen or portion thereof with animated graphical user interface showing an image in the sequence showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof; and,

FIG. 10 is a tenth image thereof.

The broken line showing of a display screen or portion thereof in all views forms no part of the claimed design. The appearance of the image transitions sequentially between the images shown in FIGS. 1-10. The process or period in which an image transitions to another forms no part of the claimed design.
